HARVEY D. REED, OF ABINGTON, AND HARRISON H. KENT, OF WHITMAN, MASSACHUSETTS, ASSIGNORS TO REGAL SHOE COMPANY, OF WHITMAN, MASSACHUSETTS, A CORPORATION OF MASSACHUSETTS

ART OF MAKING SHOE UPPERS

Application filed July 31, 1930. Serial No. 471,950.

This invention relates to the construction of shoes and more especially to the construction of the shoe upper before it is secured to the shoe bottom.

To understand fully the nature of this invention and its relation to prior art practice, it should be pointed out, by way of preliminary, that the common practice in shoe making is to cut out the so-called toe lining, that is, the inside layer of cloth or other material underlying the vamp and toe of the upper, in two lateral pieces which are stitched respectively to the adjacent sides of the quarter lining leaving the toe lining open down the middle for the convenient performance of the later stitching operations and the eyeleting of the vent.

After the quarter has been stitched and the edges of the vent eyeleted, the toe lining is then closed by uniting the two parallel adjacent edges together by overlapping them and stitching them preparatory to stitching on the vamp itself. The objection to this method, however, is that it leaves a thick seam down the middle of the forepart from the instep to the toe, which by its pressure on the sensitive underneath portion of the foot of the wearer very frequently causes much discomfort.

It has been proposed to make the toe lining in one entire piece, which is then stitched at its rear edge to the forward edge of the quarter lining, but when this is done the remainder of the stitching must be done on a stitching machine having a cylindrical work support which, being much slower in operation, involves additional labor cost and furthermore the difficulty of eyeleting the upper after the vent has been closed in front by stitching on the one-piece toe lining substantially increases the expense of the eyeleting operation, which involves much more time and labor under such conditions.

The present invention is intended to get rid of the objectionable medial seam over the medial line of the foot, while at the same time avoiding the additional expense involved in previous methods using a one-piece toe lining.

To this end the invention is characterized

by the use of a one-piece toe lining, which is united in the first instance at only one rear edge to the corresponding forward edge of the quarter lining of the shoe, the other half of the rear edge of the one-piece vamp lining being left open unstitched to the rear portion of the upper. This permits the stitching of the outside quarter to the quarter lining, the latter on the open side being provided or formed with an extension which can be stitched readily to the open edge of the toe lining after the upper edges of the quarter lining and the quarter have been stitched together and the eyelets have been inserted on both sides of the vent by the usual eyeleting machine. This and other features of the invention will be described in the following specification and will be defined in the claims hereto annexed.

In the accompanying drawings we have illustrated two slightly different forms embodying the principles of this invention, in which

Fig. 1 is a perspective view showing the quarter lining and the toe lining united by a preliminary row of stitching, the quarter lining having a forward extension on the open or unstitched side.

Fig. 2 is a perspective view of a shoe upper showing the quarter lining and toe lining united and the former stitched to the quarter or outside rear member of the upper and having the eyelets inserted.

Fig. 3 is a side elevation showing the open rear end of the toe lining stitched to the forward extension of the quarter lining preparatory to attaching the vamp or outer forepart of the upper to complete the construction of the upper before it is lasted to the inner sole.

Fig. 4 is a side elevation of the completed shoe, the vamp and the quarter being partly broken away to show the relation of the interior lining members.

Figs. 5 to 8 show a series of views corresponding to Figs. 1 to 4, respectively, of a modified form of construction, in which the forward extension of the quarter lining on the open side is integral with the quarter lining.

Referring now to Fig. 1 of the drawings, the quarter lining 2 is cut out in the usual form and comprises the heel-embracing portion 2^a having the narrow forward lateral extensions 2^b and 2^c. To one lateral forward extension 2^c is stitched a piece of fabric 5 forming a further forward extension toward the bottom line of the shoe on one side of the quarter lining piece. The vamp lining 3 is cut out in one piece and is united on one side, preferably the outer side of the shoe, by a row of stitching 4 to one forward lateral edge of the quarter lining. The other side, preferably the ball side of the toe lining, is left open or unstitched to afford easy and convenient access for the carrying on of subsequent operations.

Inasmuch as the front of the quarter lining is not closed, but is left open, it is possible to readily apply the outer quarter 6, usually of upper leather, over the quarter lining 2 and unite the quarter member 6 with the quarter lining 2 by a row of stitches 7 running from the forward edge of the quarter and quarter lining around the entire upper edge of the quarter and quarter lining, as shown in Fig. 2.

While the front of the quarter is still open it is also possible to readily and conveniently affix the eyelets along both edges of the vent.

The next operation in the process is the uniting of the open rear edge of the toe lining 3 with the forward extension 5 of the quarter lining by means of the seam 8, before which operation the tongue will have been inserted and stitched forwardly of the vent.

The various operations of stitching together the quarter and the quarter lining around their upper edges and the eyeleting of the vent flaps can be performed with the same facility and low cost, as could be done when the forepart was left open as in the case of the two-part toe lining, and yet no seam is produced over the instep and toe portions of the foot.

The modified form shown in Figs. 5 to 8 dispenses with a separate forward extension piece 5 seamed to the quarter lining, as above described. In this case, the quarter lining 20 is cut to provide the extension 20^a, which extends far enough beyond the adjacent edge of the quarter 21 to permit the easy and convenient closing of the vent by stitching the opened rear edge of the quarter lining 3 to the extension portion 20^a of the quarter lining after the quarter has been stitched to the quarter lining and the eyelets have been inserted, the seaming along the line 22 being the final operation in thus assembling the quarter, its lining and the toe lining together preparatory to stitching on the vamp 10, which is united to the previously formed structure by a seam corresponding to seam 11.

Usually the quarter lining can be cut with the integral extension 20^a for seaming to the open side of the toe lining without involving expense for extra material, since some material is wasted or lost at this point in the cutting of the quarter lining according to the usual form.

The actual saving in labor cost involved in the above described methods of constructing the shoe upper over previous methods, where an integral toe lining was used, amounts to a very substantial item in the manufacture of popular priced shoes and, therefore, this improvement results in the production of a shoe upper having no medial seam in its toe lining, but at a cost no greater than in cases where the medial seam construction has heretofore been used.

It will therefore be seen that by stitching the rear interior edge of the toe lining to the forward edge of the quarter lining on one side, only, of the medial line, the other side is left open to permit the uniting of the outside quarter member with the inner quarter lining member around the whole upper edge, including the edges of the vent which still remain open to facilitate this stitching and to facilitate the affixing of the row of eyelets along each edge of the vent. Since in either form the forward extension of the quarter lining projects beyond the adjacent forward edge of the quarter, there is no difficulty in closing the upper or vent by uniting the free rear edge of the toe lining to the forward extension of the quarter lining preparatory to attaching the vamp in the usual way.

It will be observed that in both forms the rearwardly extending portions of the one-piece toe lining are of unequal length, the longer portion being attached to the shorter forward portion of the quarter lining, while the shorter rearwardly extending portion is stitched to the forward extension of the toe lining on the opposite side of the shoe. Preferably the forward extension piece of the quarter lining will be stitched to the quarter lining on the ball or inner side of the upper.

What we claim is:

1. Improvement in the art of making shoe uppers which consists in stitching the rear edge of a one-piece toe lining to the forward edge of a quarter lining on one side only of the medial line of the upper leaving the vent of the upper open, then stitching an exteriorly applied prepared counter member to the quarter lining along their entire upper edges, including the edge portion subtending the vent, and eyeleting the edge portions of the vent, and thereafter closing the vent by stitching to a forward extension of the quarter lining the open rear edge of the toe lining.

2. Improvement in the art of making shoe uppers which consists in uniting a one-piece toe lining and the quarter lining of the upper on one side only of the vent, then applying a

prepared quarter outside the quarter lining and stitching its upper edge to the upper edge of the quarter lining and, eyeleting the vent sub-tending portions of such upper edge portion, and thereafter stitching the open rear edge of the toe lining to a forward extension of the quarter lining.

3. A shoe upper embracing in its construction, a prepared quarter member and its inside lining provided on one side of the vent with an extension projecting forwardly of the edge of the quarter, and a one-piece toe lining having its interior rear edges stitched to the forward extension of the quarter lining on one side and to the forward edge of the quarter lining on the other side of the upper.

4. A shoe upper embracing in its construction an outside quarter member, its interior lining member stitched thereto and having stitched to its forward outer edge an extension piece that is dimensioned to project beyond the forward edge of the quarter lining, and a one-piece toe lining whose rear interior edge is stitched to the forward edge of the quarter lining on one side of the medial line and the forward edge of said extension piece on the opposite side of said medial line.

5. A shoe upper embracing in its construction, an outer quarter member, an interior lining therefor stitched thereto provided with a forward extension, a toe lining, one of whose rearwardly extending portions on one side of the medial line is shorter than the other, said toe lining having the rear edge of its longer portion stitched to the edge of the quarter lining and the rear edge of its shorter portion stitched to the edge of said quarter lining extension.

6. A shoe upper embracing in its construction, an outside quarter, an inside quarter lining having forwardly extending lateral portions each side of the medial line of unequal length, a one-piece toe lining having rearwardly extending lateral portions of unequal length, the longer of which is stitched to the shorter forward side of the quarter lining and the shorter of which is stitched to the longer forward side of the quarter lining.

In witness whereof, we have subscribed
50 the above specification.
